INTERNAL-EXPANDING BRAKING DEVICE

Wilfred Dell Koch, Troyeville, Johannesburg,
Transvaal, Union of South AfricaApplication August 3, 1943, Serial No. 497,188
In the Union of South Africa October 10, 1942

3 Claims. (Cl. 188—78)

1

This invention relates to improvements in braking and clutching devices of the internal-expanding type and constitutes an improvement in or development of the invention described in the specification of my earlier co-pending U. S. A. patent application Serial No. 406,417, filed August 11, 1941, now U. S. Patent No. 2,334,935.

One of the advantages flowing from the application of this prior invention to the two-shoe type of vehicle brake, was that, due to the anchoring pivot bolt being located some distance inwardly of the brake shoes, and circumferentially rearwardly of the common pivot pin, application of the brake caused the lower or heel portions of the shoes to move towards the brake drum simultaneously with an outwardly expanding movement of the top or toe portions thereof. This arrangement resulted in reducing the tendency of the self-energising shoe to cause snatching and consequent locking and skidding of the wheels at high speeds, but suffered from the disadvantages that at slow speeds greater brake pedal pressure was required for effective braking, and that the heel portions of the brake shoe linings tended to wear more quickly than the upper or toe portions thereof.

It is to be understood that the above remarks apply to the particular arrangement of the braking shoes as illustrated in the drawings of the aforesaid U. S. Patent No. 2,334,935. On referring to Fig. 1 of these drawings it will be seen that the anchor bolt is positioned at a considerable circumferential distance away from the common pivot pin of the two shoes, and at a substantial distance to one side of the vertical centre line of the brake drum, whereby application of the brakes gave a preponderantly radial movement to the heel portions of the brake shoes.

According to one feature of the present invention the anchor bolt is positioned substantially close to and inwardly of the said common pivot pin of the brake shoes, so that application of the brake by outward expansion of the toe ends of the brake shoes by known mechanical or hydraulic means, imparts a simultaneous and similar outwardly expansive movement, as well as a slight outwardly radial movement to the heel ends of said shoes, whereby wear on the shoe linings is more evenly distributed and snatching by the self-energising shoe is prevented.

According to a preferred arrangement for achieving this result, the axis of the anchor bolt is positioned on the rearward side of a radial line passing through the axis of the brake drum

5 and the axis of the aforementioned common pivot pin connecting the heel ends of the brake shoes. The term "rearward" being used in relation to the normal direction of rotation of the brake drum.

The present invention is also intended to include a simplified construction of brake having the above described features but in which the cam-shaped automatically adjustable stop members are dispensed with, and the usual manually adjustable eccentric stop members substituted therefor. An advantage of this form of the invention, besides simplicity, resides in its capability of being employed for the purpose of converting existing types of brakes, by the making of minor alterations thereto.

This simplified form of the invention may be preferred in cases where cheapness and simplicity are the main considerations.

20 A further feature of the invention resides in the substitution for the single tension brake-withdrawal spring of the aforesaid U. S. Patent No. 2,334,935, connecting the two top or toe ends of the brake shoes, of two tension springs, one of 25 which connects the top or toe end of the rear or non-self-energising shoe to an anchoring point on the back plate of the brake drum arranged substantially horizontally in line therewith, while the other is connected between a point on the 30 self-energising shoe intermediately of its ends, and a point on said back plate adjacent the point to which the first mentioned spring is attached. By this provision a more rapid and even withdrawal of the brake shoes is secured on 35 release of the brake pedal. It will be understood from the above description that, with the normal brake arrangement having the toe ends of the brake shoes above the wheel axis, the first-mentioned spring extends in a substantially horizontal direction while the second extends in a substantially vertical direction.

According to a modification of this feature, the spring connecting the toe ends of the shoes remains unchanged, as in the aforesaid U. S. 45 Patent No. 2,334,935, but a second spring, arranged as above described is provided between an intermediate point of the self-energising brake shoe and an anchor point on the back plate.

According to yet a further feature of the invention, the friction washers which, as described in the aforesaid U. S. Patent No. 2,334,935, are pressed against the pivotally mounted cam shaped stop members by the compression springs threaded onto the stop pins, are feather-keyed 50 to said stop pins so as to prevent rotation there-

of. This provision is necessary to overcome the tendency of these springs to disturb the settings of the stop members. It was found that due to the resilience of a spring in a circular direction, about its axis, the setting of a stop member was sometimes disturbed by a slight easing back movement owing to the reaction of a spring against the rotational movement imparted to it by the stop member while being re-set.

To enable the invention to be more clearly understood and carried into practice, reference is now made to the accompanying drawings, in which like references denote like parts throughout the several views.

In the drawings:

Fig. 1 is a vertical section taken through the drum of a brake assembly constructed and arranged according to the invention.

Fig. 2 is a similar view showing an alternative arrangement.

Fig. 3 is a fragmentary sectional detail view to an enlarged scale, taken substantially on line III—III of Fig. 2.

Fig. 4 is a perspective view showing a friction washer and its stop pin in separated relationship, and

Fig. 5 is a diagram showing relative positions of the anchor bolt and pivot pin.

Referring to Fig. 1 of the drawings reference 1 denotes the axle of a vehicle wheel to which a brake drum 2 is secured in known manner, and for which the fixed back plate 4 forms a closure. Co-acting internally with the brake drum 2 is a rear brake shoe 5a and a front or self-energising brake shoe 6a, both pivotally connected together adjacent their heel ends by the common pivot pin 7. Outward expansion of the top or toe ends of the brake shoes for brake applying purposes, is effected by means of the usual hydraulic cylinder 8. The self-energising shoe 6a is pivotally mounted on the anchor bolt 13, which is located inwardly of the pivot pin 7, and a small angular distance rearwardly of a radial line 14 passing through the axes of the axle 1 and said common pivot pin 7. This angular distance G is of the order of 2 to 3 degrees as compared to about 30 degrees in the case of the illustrated modification of the invention of the aforesaid U. S. Patent No. 2,334,935. By this modified arrangement it will be apparent that an expansive or opening movement of the toe ends of the shoes 5a and 6a, will impart a simultaneous and substantially similar movement to the heel ends of said shoes due to the resulting rotational movement of the pivot pin 7 about the axis of the anchor bolt 13, which thereby causes an expansive movement of said heel ends. In addition, due to the axis of the anchor bolt 13 being on the rearward side of the centre line 14, a small simultaneous outward or substantially radial movement is imparted to these heel ends. These two movements result in a more effective and even distribution of brake pressure on the drum 2 and consequent decrease in brake lining wear and counteract any tendency for the self-energising shoe 6a to snatch or bind, particularly at high road speeds with the consequent heavy application of the brakes required for stopping or slowing down purposes.

The lever arms 15a and 17a operate to adjust the cam-shaped stop members 10a and 11a in the same manner as described with reference to the equivalent parts in the aforesaid U. S. Patent No. 2,334,935.

The extent of the aforementioned outward or substantially radial movement imparted to the heel

ends of the shoes 5a and 6a, will depend upon the distance between the pivot pin 7 and the anchor bolt 13 as well as upon the aforesaid angular distance G. For normal purposes this distance will be from $\frac{1}{4}$ to $\frac{1}{3}$ of the distance between the pivot pin 7 and the axis of the axle 1 or center of the brake drum 2.

A further feature of the present invention resides in the provision of two brake-withdrawal springs in place of the single spring 9 of the above referred to prior patent. In this case a horizontally disposed tension spring 16 is connected adjacent the toe end of the rear brake shoe and to an anchor bracket 17 fixed to the back plate 4, while a second substantially vertically disposed tension spring 18, is connected between the lever arm 17a and the aforesaid bracket 17. It will be noted that this point of connection is more or less midway between the ends of the shoe 6a. It has been found that this arrangement of the springs gives a positive, even and rapid withdrawal of the shoes on release of the brake-applying pedal or the like.

Figs. 2, 3 and 4, show further modifications in the invention, in which the automatically adjusted cam-shaped stop members 10a and 11a, are replaced by manually adjustable stop members 20 of the usual cam or eccentric type. This substitution results in the lever arms 15a and 17a being dispensed with, so that a simpler and cheaper construction of brake is provided.

In other respects the brake shoes 5b and 6b operate in a similar manner to their counterparts 5a and 6a of Fig. 1. A lug 21 is however provided as the connecting means for the lower end of the spring 18.

According to another feature of the invention which is applicable to all modifications, an improved construction of friction washer 22a is substituted for the flat friction washer 22 of the aforesaid U. S. Patent No. 2,334,935. This friction washer 22a is provided with a flange 23 adapted to be a sliding fit on the hollow stop pin 24, and in addition is provided with a keyway 25 which is arranged to co-act with the feather key 26 on the stop pin 24, so that said washer may move axially but is prevented from rotating. In the assembly shown in Fig. 3, the stop member 20 which is permanently attached to its fixing pin 27 is at all times in frictional contact with the washer 22a by reason of the compression spring 28. For adjusting purposes the nut 29 is loosened and the fixing pin 27 rotated in the required direction by means of the flats 30 on the end thereof, whereafter the nut 29 is tightened to secure the stop member 20 in its new setting.

Fig. 5 shows diagrammatically the difference between the present invention and the invention of the parent U. S. Patent No. 2,334,935.

In the aforesaid U. S. Patent No. 2,334,935, the anchor bolt 13 is positioned at an angular distance A of preferably 44 degrees from the vertical centre line 40, whereas in the present invention this angle is of the order of 15 degrees, as shown by reference C. In both cases the angular displacement B of the pivot pin 7 is of the order of 13 degrees. The radius R of the anchor bolt 13 from a centre O displaced as shown by an amount D of $\frac{1}{22}$ of the diameter of the brake drum, is of the order of .3 of the diameter of the brake drum, while the radius P of the pivot pin 7 from the true centre is of the order of .43 of the diameter of the brake drum.

It is to be understood that these dimensions

refer to the normal size of brake drum as used on road motor vehicles.

The term "rearward" as used in this specification and in the appended claims has reference to the direction away from the front of the vehicle provided with the brake according to the invention.

What I claim is:

1. An improved brake of the internal-expanding type, comprising a brake drum, a backing plate therefor and two pivotally connected arcuate shoes co-acting with said brake drum over substantially equal effective areas and severally provided with a heel end and a toe end, a common pivot pin connecting the heel ends of said shoes, the said pivot pin being slightly rearwardly displaced with respect to the vertical axis of the drum, linings on said shoes, an anchor bolt on said backing plate, the pivoted end of one of said shoes being extended beyond the common pivot pin and being pivotally attached to said anchor bolt on the backing plate, an adjustable stop member arranged to locate each shoe in its retracted position with respect to the drum, the arrangement being such that, irrespective of the condition of wear of the shoe linings, a constant minimum clearance is maintained between said linings and the brake drum by the normal application of the brake, said anchor bolt being positioned substantially close to and inwardly of the common pivot pin of the shoes on the rearward side of a radial line passing through the axis of the brake drum and the axis of the said common pivot pin, the rearward angular displacement of the axis of the anchor bolt with respect to the axis of the common pivot pin being of the order of from 5 to 15 degrees, whereby application of the brake by outward expansion of the toe ends of the shoes imparts a simultaneous and similarly outwardly expansive movement as well as a slight outwardly substantially radial movement to the heel ends of said shoes, so that initial frictional contact with the brake drum takes place below the center line thereof, whereby wear on the shoe linings is more evenly distributed and snatching is prevented.

2. An improved brake of the internal-expanding type, comprising a brake drum, a backing plate therefor and two pivotally connected arcuate shoes co-acting with said brake drum over substantially equal effective areas and severally provided with a heel end and a toe end, a common pivot pin connecting the heel ends of said shoes, the said pivot pin being slightly rearwardly displaced with respect to the vertical axis of the drum, linings on said shoes, an anchor bolt on said backing plate, the pivoted end of one of said shoes being extended beyond the common pivot pin and being pivotally attached to said anchor bolt on the backing plate, an adjustable stop member arranged to locate each shoe in its retracted position with respect to the drum, the arrangement being such that, irrespective of the condition of wear of the shoe linings, a constant

minimum clearance is maintained between said linings and the brake drum by the normal application of the brake, said anchor bolt being positioned substantially close to and inwardly of the common pivot pin of the shoes, the distance between the said anchor bolt and pivot pin being of the order of from $\frac{1}{4}$ to $\frac{1}{3}$ of the distance between said pivot pin and the axis of the brake drum, whereby application of the brake by outward expansion of the toe ends of the shoes imparts a simultaneous and similarly outwardly expansive movement as well as a slight outwardly substantially radial movement to the heel ends of said shoes, so that initial frictional contact with the brake drum takes place below the center line thereof, whereby wear on the shoe linings is more evenly distributed and snatching is prevented.

3. An improved brake of the internal-expanding type, comprising a brake drum, a backing plate therefor and two pivotally connected arcuate shoes co-acting with said brake drum over substantially equal effective areas and severally provided with a heel end and a toe end, a common pivot pin connecting the heel ends of said shoes, the said pivot pin being slightly rearwardly displaced with respect to the vertical axis of the drum, linings on said shoes, an anchor bolt on said backing plate, the pivoted end of one of said shoes being extended beyond the common pivot pin and being pivotally attached to said anchor bolt on the backing plate, an adjustable stop member arranged to locate each shoe in its retracted position with respect to the drum, the arrangement being such that, irrespective of the condition of wear of the shoe linings, a constant minimum clearance is maintained between said linings and the brake drum by the normal application of the brake, said anchor bolt being positioned substantially close to and inwardly of the common pivot pin of the shoes on the rearward side of a radial line passing through the axis of the brake drum and the axis of the said common pivot pin, the rearward angular displacement of the axis of the anchor bolt with respect to the axis of the common pivot pin being of the order of from 5 to 15 degrees, whereby application of the brake by outward expansion of the toe ends of the shoes imparts a simultaneous and similarly outwardly expansive movement as well as a slight outwardly substantially radial movement to the heel ends of said shoes, so that initial frictional contact with the brake drum takes place below the center line thereof, whereby wear on the shoe linings is more evenly distributed and snatching is prevented, a tension spring connecting the toe end of the rear shoe to an anchoring point on the said backing plate arranged substantially horizontally in line with said end, and a second tension spring extending between a point on the other shoe intermediately of its ends and a point on said backing plate adjacent the point to which said first-mentioned spring is attached.

WILFRED DELL KOCH.
